J. D. PERKINS.
REAR END SEARCH LIGHT.
APPLICATION FILED JULY 17, 1913.

1,092,450.

Patented Apr. 7, 1914.

UNITED STATES PATENT OFFICE.

JAMES D. PERKINS, OF WASHINGTON, DISTRICT OF COLUMBIA.

REAR-END SEARCH-LIGHT.

1,092,450.

Specification of Letters Patent. Patented Apr. 7, 1914.

Application filed July 17, 1913. Serial No. 779,599.

To all whom it may concern:

Be it known that I, JAMES D. PERKINS, a citizen of the United States, residing at Washington, in the District of Columbia, have invented certain new and useful Improvements in Rear-End Search-Lights; and I do hereby declare the following to be a full, clear, and exact description of the invention, such as will enable others skilled in the art to which it appertains to make and use the same.

This invention relates to safety devices for railways and has for an object to provide means in the nature of a searchlight attached to the rear end of a train for throwing an upwardly directed beam so that when the train enters a cut, this beam can be seen by the crew of a following train and will denote the presence of a train in the cut. A further object in mounting the searchlight on the rear end of the train is that due to the sway of the train, the ray of light will be oscillated, and thus present visible evidence to the following train that a train in motion is in the cut, while on the other hand should the train in the cut be halted, the ray will be stationary, and thus present visible evidence to the following train that the train in the cut is stopped.

A further object of the invention is to provide a shield for the searchlight, such shield protecting the lens of the searchlight against accumulations of dust and cinders, this shield being adjustably mounted so as to be positioned in such a manner as to most effectively perform its function.

With the above objects in view the invention consists of certain novel details of construction and combination of parts hereinabove after fully described and claimed, it being understood that various modifications may be made in the minor details of construction within the scope of the appended claim.

In the accompanying drawing illustrating this invention:—Figure 1 is a side elevation showing the rear portion of the rear coach of a train in a cut and showing the application of my invention thereto. Fig. 2 is an enlarged view of the searchlight applied, showing the parts in side elevation. Fig. 3 is a longitudinal sectional view through the parts shown in Fig. 2. Fig. 4 is a rear elevation of the parts shown in Fig. 3. Fig. 5 is an enlarged longitudinal sectional view showing the electrical connection. Fig. 6 is

a fragmentary side elevation showing the shield in one of its adjusted positions.

Referring now to the drawing in which like characters of reference designate similar parts, 10 designates the rear end of the rear coach of a train, the same being shown passing through a railway cut 11.

In carrying out my invention I provide a searchlight 12 of ordinary type having an attaching socket 13 adapted to be removably engaged with a plug 14 carried by a plate 15 that is fastened in any preferred manner to the extreme rear end of the car roof 16, said plug and socket being so arranged that the searchlight will project its ray obliquely upwardly as shown at 17. By virtue of the searchlight being positioned as above described on the rear end of the car roof, the swaying of the car will impart an oscillatory movement of considerably wide extent to the ray of light so that a train following the first mentioned train into the cut, will have visible evidence that a moving train is in the cut. On the other hand should the train be stopped for any reason, the ray will remain stationary, and thus the following train will have visible evidence that a train has stopped in the cut. This signal therefore enables the following train to be slowed down or stopped in ample time to prevent a rear end collision with the train in the cut.

The searchlight socket 13 is preferably provided with positive and negative terminal pins 18 and 19 which are connected to the corresponding conductor wires 20 and 21 of the incandescent lamp 22 in the searchlight, these pins being engageable with corresponding sockets 23 and 24 disposed within the bore 25 of the attaching plug 14 carried by the car, these sockets being connected to corresponding conductor wires 26 and 27 that lead to the generator or other source of electricity with which the train is equipped. A set screw 28 is employed to securely fasten the searchlight socket to the attaching plug 14 so that jarring loose of the searchlight due to vibration of the train will positively be prevented.

An arched shield 29 is hinged at the rear edge to the top of the searchlight as shown at 30 and projects along the sides of and in front of the searchlight, the sides of the shield being equipped with arcuate slots 31 that receive pins 32 carried by the searchlight sides, there being thumb nuts 33

threaded on these pins and serving to clamp the shield in adjusted positions on the searchlight. This shield projects upwardly at a slight angle from the searchlight so that cinders, dust and the like will be deflected from the searchlight and thus accumulations on the lens with consequent obstruction and dimming of the ray will be positively prevented.

10 From the above description it will be seen that I have provided an extremely simple and efficient night signal which will effectively operate to prevent rear end collisions in railway cuts.

15 What is claimed, is:—

An attachment for removably holding a searchlight in position to direct its beam obliquely upward including an elbow having

a horizontal leg provided on the extreme end with an integral attaching plate and having 20 a vertical leg, a tube receiving said vertical leg within its lower end and having a horizontal leg terminating in a searchlight attaching plate disposed obliquely across the last named horizontal leg, means securing 25 said tube removably to the vertical leg of said elbow, and electrical connections extending through the bores of said elbow and said tube.

In testimony whereof, I affix my signature, 30 in the presence of two witnesses.

JAMES D. PERKINS.
